UNITED STATES PATENT OFFICE

2,209,675

FRACTIONATING TOWER

Dan L. Dodds, Galveston, Tex.

Application September 6, 1938, Serial No. 228,561

3 Claims. (Cl. 261—114)

This invention relates to a fractionating tower.

The invention embodies certain improvements over that type of fractionating tower disclosed in my co-pending application, Serial No. 197,164, filed in the United States Patent Office on March 21, 1938.

An object of the invention is to provide an apparatus of the character described specially designed to be employed for the purpose of separating vapors whereby those not of the desired characteristics may be condensed and separated from those which are of the desired characteristics, the condensed vapors being returned, if desired, for further treatment.

More specifically the invention relates to apparatus designed to be employed in fractional distillation, absorption, condensation or stripping of liquids or gases as the same move in an approximately horizontal direction through the tower.

The invention embodies the advantages of that type of construction disclosed in the co-pending application above referred to and in addition thereto novel types of sealing pans and bubble caps mounted in vertical partitions and of such novel arrangement and construction as to materially increase the capacity of the tower and more efficiently separate the lighter from the heavier vapors, the latter being condensed out and returned for such retreatment as may be desired.

With the above and other objects in view the invention has particular relation to certain novel features of construction, arrangement of parts, and use, examples of which are given in this specification and illustrated in the accompanying drawings, wherein:

Figure 1 shows a fragmentary, vertical-sectional view taken on the line 1—1 of Figure 3.

Figure 2 shows a fragmentary, vertical-sectional view taken on the line 2—2 of Figure 3.

Figure 3 shows a fragmentary, longitudinal, sectional view taken on the line 3—3 of Figure 2.

Figure 4 shows a fragmentary, perspective view, partly in section of one of the sealing pans employed.

Figure 5 shows a plan view of another embodiment of said pan.

Figure 6 shows a plan view of still another embodiment.

Figure 7 shows a fragmentary, side elevation, partly in section, showing a sealing pan assembly.

Figure 8 shows a cross-sectional view of said assembly taken on the line 8—8 of Figure 7.

Figure 9 shows a fragmentary, bottom view of the sealing pan illustrating another embodiment.

Figure 10 shows a plan view of still another embodiment of the sealing pan.

Figure 11 shows a cross-sectional view thereof taken on the line 11—11 of Figure 10.

Figure 12 shows a fragmentary, vertical-sectional view of the tower illustrating the type of sealing pan assembly shown in Figure 10, and Figure 13 shows a side view, partly in section, of the complete tower.

Referring now more particularly to the drawings wherein like numerals of reference designate the same parts in each of the figures, the numeral 1 designates an outer shell or container which is preferably so disposed that the fluid will follow, in general, an approximately horizontal course from inlet to outlet. Mounted in the shell and spaced a selected distance apart are similar vertical partitions 2 which are anchored to the walls of the container by brackets as 3 and whose margins are in sealed engagement with the walls of the container. The partitions have the rectangular openings 4 therethrough which are preferably in alignment. Series of collecting, or sealing, pans are mounted in the respective openings of the partitions as best shown in Figures 1, 2 and 7. As shown in Figures 1, 2, 11 and 12, bubble caps hereinafter more particularly described are combined with the sealing pans of the assemblies shown in said figures. The type of collecting pan, or sealing pan, illustrated in Figures 1, 2 and 3 is indicated by the numeral 5, Figure 5. Each pan of this type has a surrounding marginal upstanding flange 6 and has the rectangular, transversely extending, upstanding weirs 7, 7. The pans are arranged in series, one series for each partition 2, and the pans of each series are arranged one above the other as shown in Figures 1 and 2. The ends of the pans are anchored to the corresponding partitions by means of their brackets as 8, as illustrated in Figures 1, 2, 3, 7 and 12. Depending from the pans 5 are the bubble caps 9. The bubble caps of each pan depend down into the pan beneath. They extend transversely of the pan as shown more clearly in Figure 3 and are preferably rectangular in horizontal cross-sectional contour. The lower ends of the bubble caps are serrated forming the deep notches 10. The apexes of the notches are approximately on a level with, or slightly above the upper margins of the weirs 7, and, it is to be noted, that the upper margins of the weirs 7 are located slightly beneath the upper margins of the surrounding sides or flanges 6 of the corresponding pans 5. The forward walls of the bubble caps of each pan, of the form

shown in Figures 1, 2 and 3 have a common rear wall 11 which is provided with the inlet openings 12 for the advancing vapors. The forward wall 13 of each bubble cap is closed.

5 The vapors to be dephlegmated advance from the entrant end of the tower, in the direction of the arrow in Figure 3, toward the discharge end passing through the openings of each series into the corresponding bubble caps. The heavier elements will be condensed on the walls of the bubble caps and drained down into the respective pans beneath so as to eventually maintain the serrated edges of the caps submerged, the lighter elements bubbling through the entrapped liquid and passing on from one series of bubble caps to the next and eventually collecting in the final compartment 14 and passing thence outwardly through a suitable vapor outlet line 15. Each partition 2 is provided, near its lower margin with a transverse return slot 16, and in front of said slot, is provided with a transverse baffle 17 which extends upwardly the required distance above the upper margin of the corresponding slot thus provided for the return of the residue from compartment to compartment.

10 The condensate will collect in the pans 5 of the respective series.

15 The weirs of the pans 5 define the depending pockets 18, 19 into which the bottoms of the respective pans are formed. Return pipes 20 lead from the respective pockets 18, of the pans of one series into the corresponding end pockets 18 of the corresponding pans in the rear and return pipes 21 lead from the respective pockets 19 of the pans of one series into the corresponding end pockets 19 of the corresponding pans in the rear. The condensate rising above the level of the corresponding weirs of any pan will therefore overflow into the pocket 18, or 19, of said pan 20 and will flow thence through the corresponding pipe leading rearwardly therefrom to the corresponding pocket of the next pan in the rear, thus overflowing the weir above and flowing into the corresponding pan. The condensate thus 25 eventually flowing rearwardly from one series of pans to the next series in the rear. Any excess condensate collecting into and overflowing any of the pans will fall down into the bottom of the shell or tower and will return from compartment 30 to compartment through the slots 16 overflowing the corresponding baffles 17 and thus rising to a level to submerge the lower serrated ends of the lower bubble caps 9.

35 It will be noted that the returning condensate entering each pan from the corresponding pan in front will enter at one end of the pan and travel along said pan overflowing the weir at the other end thereof and continuing its rearward course.

40 In Figure 4 there is shown another embodiment of the collecting pan, or sealing pan, 5a having the end weirs as 1a and provided with the inlet openings 12a in the forward wall. With this type of pan the condensate overflowing the end weirs, as 1a, will pass into the end pockets as 18a. This type of pan 5a is provided with overflow pipes 20a, at each end and 21a arranged intermediate the ends whereby the excess condensate may overflow from one pan into the pan beneath. 45 In other respects the pan 5a is substantially similar to the pans 5 in Figures 1 and 2.

50 In the form shown in Figures 6, 7 and 8 another embodiment of the collecting pan or sealing pan is illustrated and indicated by the numeral 5b. It has the upstanding marginal rim

5 or flange 6b and the diagonally opposite weirs 7b. The ends of the pans 5b are secured to the corresponding partitions 2 by the brackets 8 as shown in Figure 7. This type of pan has the overflow pipes 20b, 21b for permitting return circulation of the condensate from series to series as hereinabove described.

55 As clearly shown in Figure 8 the pan assembly, embodying the type of pan shown in Figure 6, does not embody the bubble caps, properly speaking, but depending from each pan, into the compartment beneath, there is a centrally located, longitudinal baffle 22 whose lower margins are serrated providing the notches 23 and the pans are spaced apart vertically to permit the passage of vapor forwardly through between the pans of the series. The upper plate 22 depending into the upper pan 5b is suitably secured to the margin of the partition 2 as also clearly shown in Figures 7 and 8. The vapors passing through the series of pans 5b will be partially condensed, the heavier particles collecting in the pans in the form of condensate so as to eventually maintain the lower serrated edges of the plates 22 submerged, the lighter elements bubbling through the entrapped liquid and passing on from one series of pans to the next and eventually collecting in the compartment 14.

60 If desired the baffle, or plate, 22a, as shown in Figure 9 depending from the bottom of the pan 5c, may be formed sinuous, with its lower margins serrated thus giving somewhat greater capacity for the passage of the lighter elements and the condensation of the heavier elements.

65 Referring to Figures 10 to 12, inclusive, there is there shown another embodiment of the sealing pan or collecting pan 5d of the general shape as that of the pan 5b and having the diagonally opposite receiving pockets 18a, 19a, connected with which are the pipes 20c, 21c. The pockets 18a, 19a are separated from the pan by the respective weirs 1c whose upper margins are on a lower level than the upper margin 6c of the pan 5d. These pans are anchored to the corresponding partitions by the end brackets 8 as illustrated in Figure 12. Depending from each pan into the compartment beneath are bubble caps similar in construction and arrangement to those illustrated in Figures 1 and 2 and have a similar purpose.

70 In a compartment of the tower utilizing this type of pan 5d the condensate may flow rearwardly from pan to pan through the overflow pipes 20c, 21c and may overflow downwardly through the overflow pipe 21d arranged intermediate the ends of the pan 5d whose upper end 75 extends upwardly into the pan but terminates beneath the upper margin of the surrounding flange 6c and whose lower end extends downwardly into the compartment beneath.

75 It will thus be observed that the liquid as it collects will pass from pan to pan either in a rearward direction, or in a downwardly direction, and will finally collect at the bottom of the corresponding compartment and will pass thence from compartment to compartment to the initial compartment from which it may be discharged by any suitable discharge equipment provided for the purpose. This is very desirable as it allows the particles of the lighter fraction or constituents of a lower boiling point to pass on rather than to be entrained in constituents of a higher boiling point and to be carried back along the tower where it may pass out as residue.

80 In this type of equipment during operations there is a continuous flow of vapor forward in 75

the tower until the vapors reach the final compartment, in the present illustration indicated by the numeral 14, and from which it is conducted out by the vapor line 15 and there is also a continuous flow of liquid backwardly or in the opposite direction to the forward movement of the flow of the vapor.

It is sometimes found desirable to admit additional liquid for refluxing or for the purposes of absorption. For this purpose a line 24 has been provided which leads from a suitable source of refluxing, or absorption, liquid up through the final compartment 14 and which is connected into the forward ends of the pockets 18 of the respective pans in said final compartment.

It is, of course, to be observed that the vapors flowing through the tower from inlet to outlet will be maintained under the required pressure and temperature.

20 The fluid to be fractionated enters the initial compartment 25 through the delivery pipe 26. The compartment 25 may contain a heating coil 27, if desired, into which a heating element may be delivered through a pipe 28. Other heating means may be employed, if desired, or in some cases this heating element may be dispensed with. Leading from the compartment 25 there is an outlet line 29 whose inner end extends up into said compartment to the desired liquid level 30 and may be surrounded and enclosed by a vertical hood 30 forming a trap. This hood may be supported in any selected manner.

What I claim is:

1. In a fractionating tower having a shell and a vertical partition whose margins are in sealed engagement with the walls of the shell, said partition having an opening therethrough; a series of collecting pans mounted in said opening one above the other, each pan having upstanding side walls and end walls, means for anchoring the pans to the partition, bubble caps depending from the pans, the caps of each pan above depending downwardly into the pan beneath and whose lower ends are serrated forming deep notches whose apexes are slightly beneath the upper margins of said walls, weirs defining areas of the pans and whose upper margins are slightly beneath the apexes of the notches, inlet and

outlet conduits one entering the pan beneath the level of the corresponding weir and the other leading from the pan beneath the level of the other weir whereby fluid may flow through one conduit and overflow said weirs and pass outwardly through the other conduit.

2. In a fractionating tower having a shell and a vertical partition whose margins are in sealed engagement with the walls of the shell, said partition having an opening therethrough; a 10 series of collecting pans mounted in said opening one above the other, each pan having upstanding side walls and end walls, means for anchoring the pans to the partition, bubble caps depending from the pans, the caps of each pan 15 above depending downwardly into the pan beneath and whose lower ends are serrated forming deep notches whose apexes are slightly beneath the upper margins of said walls, weirs defining areas of the pans and whose upper margins are 20 slightly beneath the apexes of the notches, inlet and outlet conduits one entering the pan beneath the level of the corresponding weir and the other leading from the pan beneath the level of the other weir whereby fluid may flow through 25 one conduit and overflow said weirs and pass outwardly through the other conduit and an overflow pipe through which fluid may flow from one pan into another pan.

3. In a fractionating tower having a shell and 30 a vertical partition whose margins are in sealed engagement with the shell, said partition having an opening; a vertically arranged series of pans in said opening and anchored to the partition, baffling means depending from each pan 35 whose lower margins are serrated forming notches, the baffling means depending from one pan above into the pan beneath, the apexes of said notches being located beneath the upper margins of the walls of the pan into which the 40 baffle extends whereby to permit a gaseous fluid to flow forwardly through the pans in one direction, an inlet conduit entering each pan, an outlet conduit leading from each pan and means for causing the flow of condensate collecting in 45 the pans in a direction the opposite of that of the gaseous fluid.

DAN L. DODDS.
